to Nic Projector Corporation, New York, N. Y.,
a corporation of New York

Application December 21, 1935, Serial No. 55,608

8 Claims. (CL. 197—47)

My invention relates to a new and improved typewriter.

One of the objects of my invention is to provide a new and improved toy typewriter, of the type which employs a printing wheel.

Another object of my invention is to provide improved means for turning the printing member or wheel around its own axis, so as to move the desired character thereof into printing position.

Another object of my invention is to provide an improved carriage on which the printing wheel is mounted.

Another object of my invention is to provide mechanism for turning the printing wheel, by means of a movable member which is independent of the carriage of the printing wheel.

Another object of my invention is to provide a shaft which is mounted in the frame of the typewriter and whose movement turns the printing wheel around its own axis.

Another object of my invention is to provide means for holding the ribbon of the typewriter in operative position, relative to the longitudinally shiftable printing wheel.

Another object of my invention is to provide improved mechanism for actuating the printing wheel towards and away from the printing position, and to provide improved mechanism for longitudinally shifting the printing wheel for spacing purposes, either simultaneously with the printing movement, or independently thereof. Whenever I refer to a printing wheel, I wish to include a printing member of any type, which may be shifted in any manner so as to move the desired character or number to printing position.

Other objects of my invention will be set forth in the following description and drawings which illustrate a preferred embodiment thereof, it being understood that the above statement of the objects of my invention is intended generally to explain the same without limiting it in any manner.

Fig. 1 is a top plan view of the improved typewriter.

Fig. 2 is a front elevation of Fig. 1. This view is partially broken away so as to illustrate certain of the parts.

Fig. 3 is a side elevation taken at the left-hand side of Fig. 1.

Fig. 4 is a rear elevation of Fig. 1.

Fig. 5 is a sectional view on the line 5—5 of Fig. 1.

Fig. 6 is a detail elevation, partially in section, and with certain of the parts broken away,

illustrating the printing wheel and certain important accessory parts.

Fig. 7 is a sectional view on the line 7—7 of Fig. 6.

Fig. 8 is a sectional view on the line 8—8 of Fig. 6.

Fig. 9 is a partial top plan view of Fig. 1, said view being partially in section, the character plate of the frame having been removed.

Fig. 10 is a sectional view on the line 10—10 of Fig. 4.

Fig. 11 is a top plan view of the printing wheel.

The improved device comprises a frame F which can be stamped from any suitable metal. The bottom wall and the rear wall and the side walls of said frame are integral with each other.

A character plate I serves to cover a portion of the frame. Said character plate I has lips 2 which extend over the side walls of the frame F. Said lips 2 are connected to the side walls of the frame F, by means of fastening members 3.

The plate I has representations 4 of the various characters, numbers and the like.

As shown in Figs. 1 and 5, the plate I may be stamped so as to provide cup-shaped members 5 whose edges or rims are raised above the top surface of the plate I. The representations 4 can be formed in said depressions by means of painting or by pasting suitable inserts or the like.

The platen 6 is of the usual type, and it is provided with a covering sleeve 7 made of rubber or other suitable material. Said platen is mounted upon a shaft 8, which may be replaced by relatively short stud shafts, which enter recesses in said platen 6. The shaft 8 is mounted in suitable bearings which are provided in the side walls of the frame F.

The platen can be turned in the usual manner by means of members 9, which are suitably secured to the shaft or shafts 8.

As shown in Fig. 1, one of the side walls of the frame, such as the right-hand side, may be provided with an annular row of cup-shaped projections 10, which are embossed out of the material of said wall.

As shown in Fig. 10, a metal disc 11 can be fixed to an end wall of the platen 6. Said metal disc 11 is provided with a projecting arm 12, having a ball-shaped projection 14. This arm 12 is resilient, and the ball-shaped projection 14 enters the cup-shaped recesses which are formed by stamping out the projections 10. This arm provides a releasable detent, so that the platen is held yieldingly in position.

The platen is also associated with a movable

bar 15, for holding the sheet of paper which is located between said bar and the platen. Said bar 15 is mounted in perforations or bearings which are provided in the side walls of the frame

5 F. Said bar 15 is provided with a handle 16, and a spring 17 maintains said bar 15 pressed against the covering of the platen.

As shown in Figs. 3-5, the device is also provided with the usual rubber sleeves 18, which are 10 mounted upon a shaft 19.

As shown in Fig. 4, the rear wall of the frame F is provided with an extension plate 20. As shown in Fig. 4, the side walls of the frame are provided with lips 21 which are bent over the rear 15 wall of the frame.

10 The lips 21 are connected to the rear wall of the frame, at the upper edge of said rear wall, by means of rivets or other fastening members 22. The lips 21 are also located at the rear 20 surface of the extension plate 20 and fastening members 23 connect said extension plate 20 rigidly to the lips 21.

25 The extension plate 20 is provided with cut-outs so that the rubber sleeves 18 may have frictional contact with the covering of the platen 6, so that the platen 6 and the sleeves 18 and the shaft 19 turn in unison.

30 As shown in Fig. 4, the rear wall of the frame F is provided with upward extensions 24, which 30 are bent into cylindrical form, so as to provide a bearing for the shaft 19, and to space the sleeves 18.

35 The metal index bar 25 has the angular shape which is shown in Fig. 5 and the rear edge of said index bar 25 is curved into a bead. The index bar 25 is provided with end lugs 26, which are connected by means of rivets or other suitable fastening means 27 to the side walls of the frame. Said fastening members 27 also rigidly 40 connect the slotted ribbon supports 28 to the side walls of the frame.

45 The front wall of the index bar 25 is embossed so as to form a series of recesses 29, which are shown in Fig. 2 and also in Fig. 8. These recesses form a series of rack-teeth. As shown in Fig. 2, each of said recesses has a straight edge and a curved edge, in front elevation.

50 The rack-teeth formation which is provided by said recesses is clearly shown in Fig. 8. As shown in Fig. 11, the printing member 30 may be a disc, which is provided upon its periphery with any suitable number of integral printing characters 31. The printing members 31 can consist of separate type members, which may be affixed in any 55 suitable manner to the periphery of the printing wheel 30. Said printing wheel 30 is provided with a hub 32, and a set screw 33 connects said hub to a shaft 34.

60 As shown in Fig. 6, a gear 35 is keyed to the shaft 34. The gear 35 meshes with a driving gear 36, which is mounted upon a sleeve or hollow shaft 37.

65 As shown in Fig. 6, the interior surface of said hollow shaft 37 has a non-circular cross section. In this particular embodiment, said interior surface has a square cross section. Said hollow shaft 37 is longitudinally slidable upon a shaft 38, which also has a square cross section, so that the shafts 37 and 38 turn in unison.

70 As shown in Fig. 1, the right-hand end of the shaft 38 is provided with a reduced cylindrical end which is externally threaded and which extends through a circular opening in the adjacent side wall of the frame F. Said opening is smaller 75 than the end-wall of shaft 38. A nut 39 main-

tains the assembly between the reduced right-hand end of the shaft 38 and the adjacent side wall of the frame F, while permitting the shaft 38 to turn freely.

As shown in Fig. 1, the left-hand end of the 5 shaft 38 extends through a circular opening in the adjacent side wall of the frame F, said opening being sufficiently large to permit the free turning movement of the shaft 38.

A removable and knurled member 40 has a 10 friction fit upon the projecting left-hand end of the shaft 38.

A longitudinally movable carriage is provided for the printing wheel and certain associated parts. This carriage is preferably made of 15 stamped metal. Said carriage is provided with a lip 41, a first web 42, a second web 43, and a third web 44 which is provided with an inclined projection 45, having a lip 46. These parts of the carriage are integral, so that they can be 20 made by stamping a single sheet of metal into the desired shape. The web 44 and the inclined projection 45 may be stamped so as to provide strengthening ribs 47. The lip 46 can likewise be stamped so as to provide a strengthening rib 25 48. A supplemental web 49 is soldered or riveted to the web 45 and this supplemental web 49 is provided with a lip 50.

The web 42 is provided with upstanding lugs 51, to which a pair of arms 52 are detachably 30 connected by means of screws or other fastening members 53. Web 44 has downwardly turned lugs similar to lugs 51. Arms 52 are connected to the lugs of web 44 by fastening members 55. Web 44 has an additional downwardly turned 35 lug, to which arm 58 is connected by pivot pin 59. Arm 58 has a detent 60 which meshes with the teeth of gear 36. Spring 61 is connected to arm 58 and to web 44, so that detent 60 yieldably engages gear 36 to hold said gear releasably 40 after it has been turned so as to move the desired printing member 31 into operative position.

The sleeve or hollow shaft 37 is supported between the arms 52 and in the perforations of the bottom portions of said arms 52. Said sleeve 37 45 and said arms 52 move longitudinally in unison. Said sleeve 37 and arms 52 also rock in unison when plate 76 is operated. The sleeve 37 may fit frictionally in the perforations of said arms 52.

The upper ends of the arms 52 are integral 50 with a cut-out annular member 56, the cut-out portion of said member 56 permitting the printing members 31 to be pressed against the ribbon R of the typewriter.

55 The top surface of the member 56 is provided with an index scale, as shown in Fig. 1. Likewise the upper end of the shaft 34 is provided with a pointer 57, in order to indicate the operative position of the respective printing character. For example, in the position shown in Fig. 1, the 60 character "3" is in the printing position.

The annular cut-out member 56 is provided with an integral lug 62.

A lug 63 is integral with an arm 64, which is bent downwardly and angularly so as to provide 65 a web 65, which is turnably mounted adjacent the web 42. A collar 66 extends through an opening in the web 42 and the bottom of said collar is wider than said opening in the web 42. Said collar extends upwardly through an opening in the web 65 and the upper end of said collar 66 is enlarged so as to hold the web 65 turnably relative to the web 42.

A rack-member 67 is slidably mounted in an opening of the web 43. Said rack-member 67 is 75

located at the underside of the web 42. Said web 42 is provided with a slot. A pin 68 is connected to said rack-member 67 and it extends upwardly through said slot. Said pin 68 abuts a projection of the web 65, in the position shown in Fig. 8.

A spring 69 is connected to said pin 68, and to an upstanding lug of the web 42.

Hence the rack-member 67 is yieldingly maintained by spring 69, in a position in which it engages with the recesses 29. When the arm 64 is turned towards the fixed lug 62, the teeth of the rack-member 67 are released from the teeth 29 of the index bar. In the position shown in Fig. 8, web 65 is turned counter-clockwise, in order to release the teeth of rack-member 67 from the teeth 29 of bar 25.

An arm 70 is located below web 42 and it is pivotally connected at 71 to said web 42. A spring 73 is connected at one end to a lug of the web 65, and the other end of said spring 73 is connected to the upstanding lug 74 of the arm 70.

The upstanding lug 74 of the arm 70 extends upwardly through a slot of the web 42 and said upstanding lug abuts or is close to a projection 75 of the web 65 in the position shown in Fig. 8. The edge of said projection 75 which is adjacent lug 74 has a curved or cam surface. Hence, when the arm 64 is turned in the counter-clockwise direction, referring to Fig. 8, the arm 70 is turned counter-clockwise by the cam surface of projection 75 until the inner end of arm 74 is released from the recesses or teeth 29 of the index bar.

The projection 75 extends through a slot in the web 41, as shown in Fig. 5 and Fig. 8.

Hence when the arm 70 engages the rack teeth of the index bar, the projection 75 slidably enters a groove provided in the rear surface of the character plate 1.

A plate 76 is provided with integral triangular end pieces 77, which are connected by pivot pins 78 to the side walls of the frame. Said plate 76 is stamped so as to provide a curved extension 79 which is located between the lips 46 and 50. A spring 80 is connected to one of the end pieces 77 and to a pin which is fixed to the adjacent side wall of the frame. Said plate 76 is provided with integral flanges 81, whose shanks 76a extend upwardly through a suitable slot 82 of the character plate 1.

Hence, when either or both of the members 81 are depressed, the plate 76 is turned in the clockwise direction, referring to Fig. 5, and the carriage on which the printing wheel is mounted is rocked in the counter-clockwise direction, thus pressing the selected printing character against the ribbon R. The shaft 38 then rocks in unison with the carriage of the printing wheel, so that said shaft forms a rock-support for said carriage.

A spacing plate 83 is provided with a shank 85, the lower part of which extends through a slot which is formed in the plate 76. Said plate 83 is also provided with an extension 87 which is connected by tongues 84 to the plate 76. Said connection can be provided by passing said tongues 84 of the plate 87 through slots which are provided at the plate 76, and then bending such tongues.

A spring 90 is connected to a lug of the front wall of the shank 76a and to the underside of the member 83. Hence when the plate 83 is pressed downwardly the plate 76 is rocked in the clockwise direction (referring to Fig. 5). The bottom of the member 85 strikes against the bottom plate of the frame, so that the turning movement of the plate 76 is less when the member 83

is actuated, than when the members 81 are actuated. That is, the tongues 84 permit a certain relative turning movement between plates 76 and 87. When the members 81 are actuated, the plate 83 can ride upwardly with respect to the flange 76a of the plate 76.

When the plate 76 is rocked by depressing members 81, the carriage of the printing wheel is rocked so as to effect printing, as previously stated.

The ribbon R is slidably guided between lugs or guide members 90 and 91, which are suitably secured to the member 56, so that the operative part of the ribbon is held in curved form, which corresponds to the periphery of the printing member.

The operation of the device is as follows:—

The carriage of the printing wheel is freely shiftable from left to right. Said carriage cannot be shifted from right to left until the arm 64 has been turned in the counter-clockwise direction, (referring to Fig. 8), so as to release the members 67 and 70 from the stationary rack-teeth 29 of the index bar 25.

The printing position is indicated by the central member 90 of the member 56.

The operator turns the shaft 34, thus turning gear 35 and gear 36 so as to turn shaft 38 and sleeve 37, while the carriage is in the position shown in Fig. 5, until the pointer 57 is aligned with the selected character upon the index scale of the member 56. While there is sufficient friction between sleeve 37 and arms 52 to cause sleeve 37 to rock in unison with the carriage when plate 76 is operated, sleeve 37 can turn relative to arms 52. The operator then turns the plate 76 against the force of the spring 80, by pressing upon one or both members 81.

The carriage of the printing wheel now turns in unison with the shaft 38, so that the printing wheel is not turned about its own axis, when the carriage of the printing wheel is rocked. If shaft 38 were held stationary while the carriage was rocked, gear 35 would be turned. However, since the intermeshing teeth of gears 35 and 36 are moved through the same arc, when the carriage is rocked, by operating plate 76, said rocking does not turn gear 35.

The position of the parts shown in Fig. 8 corresponds to the normal position of the plate 76 which is illustrated in Fig. 5. In such position, the point of the arm 70, and the teeth of the rack-member 67, do not contact with the inner surfaces of the stationary rack-teeth 29. Likewise, and as shown in Fig. 8, the inner point of the arm 70 is longitudinally offset, relative to the pivot 71 of said arm 70.

Hence, when the plate 76 is rocked so as to rock the carriage of the printing wheel, the inner point of the arm 70 is pressed against the surfaces of the rack-teeth 29, which tends to cause said arm 70 to turn in the counter-clockwise direction against the force of the spring 73, in the position of the parts which is illustrated in Fig. 8.

The carriage of the printing wheel cannot turn, save for the rocking movement which is produced by the movement of the plate 76. Hence the torque which is impressed upon the arm 70 causes the carriage to be shifted from left to right, for a distance corresponding to the space between a pair of the stationary rack-teeth 29. This longitudinal shifting is permitted by the rack member 67.

Likewise said rocking movement of the print-

ing wheel causes the teeth of the rack member 67 to be pressed yieldingly against the stationary rack-teeth 29, thus preventing any overrunning movement of the carriage of the printing wheel, 5 and limiting said longitudinal movement to a distance which is equal to said spacing of the rack-teeth 29.

At the completion of the rocking movement of the carriage and after said carriage has been 10 shifted from left to right through said predetermined distance, the character is pressed against the ribbon and the ribbon is pressed against the sheet of paper which is on the platen so that the printing is performed after the carriage has 15 been shifted from left to right, through said spacing distance.

When the members 81 are released, the spring 80 moves the plate 76 back to the normal position which is shown in Fig. 5, and the curved 20 extension 79 of the plate 76 then rocks the carriage back to the normal position which is illustrated in Fig. 5. The operator then turns the shaft 38 so as to select another character and the printing operation is then repeated.

25 If it is desired to move the carriage from left to right without printing, this can be done by depressing the member 83, until the member 85 strikes against the bottom plate of the frame, or any suitable stop.

30 The rocking movement of the plate 76 which is caused by depressing the member 83, is of less amplitude than the rocking movement which is produced by depressing the members 81. Hence, when the member 83 is depressed, the carriage of 35 the printing wheel will be shifted through said spacing distance, but without rocking the carriage of the printing wheel sufficiently to produce printing or typing.

If it is desired to move the carriage from right 40 to left, the operator moves the lug 63 towards the lug 62, thus moving the rack member 67 and the arm 70 to their inoperative positions.

It is obvious that the device can be made almost wholly from stamped metal and that it comprises a minimum number of parts so that the 45 device can be cheaply manufactured.

While I have shown a complete typewriter, it is obvious that the invention presents numerous valuable sub-combinations which can be used 50 independently of the complete combination set forth herein.

The device shows an adjustable printing member having means adapted to support the same for longitudinal sliding movement, and also for 55 movement towards and away from the platen. Said means may be a single device as specifically shown in this embodiment, or it may include a plurality of devices. Likewise the improved device shows means mounted on the frame and 60 adapted to shift the printing member so as to move a selected character thereof into printing position relative to the platen.

Whenever I refer in this connection to the frame, I refer to any part or member which is not 65 moved longitudinally in unison with the longitudinal sliding movement of the printing member.

For convenience I have used reference numerals in some of the claims. However, it is to be understood that by using such reference numerals, I do not wish to be limited to the parts or details which are illustrated in the preferred embodiment.

The position of the carriage in which a character of the printing member presses against the 75 ribbon and in which the ribbon is forced against

the paper which is on the platen, may be designated as the printing position of the carriage.

Referring to Fig. 8, it will be noted that the pivot 71 is longitudinally offset relative to the left-hand end of the arm 70, so that said end 5 contacts with a fixed part of the frame, before the printing member is moved to its printing position.

In the specific embodiment shown, said fixed 10 part of the frame has rack teeth.

Referring to Fig. 8, this illustrates what may be designated as the normal position of the carriage of the printing member, said position being also illustrated in Fig. 5.

As shown in Fig. 8, the teeth of the rack member 67 mesh only partially with the rack teeth 29 of the frame, in said normal position. Said partial meshing is sufficient to prevent the carriage from being moved to the left, unless the rack member 67 is moved away from the rack teeth by 20 the manually operated means.

The member 68 serves as a stop so as to prevent full meshing or contact between the rack member 67 and the rack teeth 29, in said normal position. In said normal position the left-hand end of the 25 arm 70 also meshes only partially with the rack teeth 29. Said partial meshing is sufficient to cause the left-hand end of the arm 70 to contact with the tips of the rack teeth 29, if it is attempted to move the carriage to the left. However, the 30 manually operated means simultaneously slide the rack member 67 and turn the arm 70 so that the members 67 and 70 are moved wholly out of mesh with the rack teeth 29, thus permitting the free sliding movement of the carriage towards the 35 left-hand end of the platen.

While I have shown a relativey short ribbon R, it would not be departing from the invention if said ribbon R were mounted on spools of the 40 usual type.

It will be noted that the carriage of the printing member is slidale relative to the ribbon and that a portion of the ribbon is held in curved form by means of the guides 90 and 91. Said curved part of the ribbon may have a curvature 45 which approximates the curvature of the printing member 30. The curvature of said part of the ribbon may be the same as the curvature of the printing member 30, although this is not necessary.

I have shown a preferred embodiment of my 50 invention, but it is clear that numerous changes and omissions can be made without departing from its spirit.

I claim:

1. In a typewriter having a frame and a platen, a shaft mounted in said frame, a carriage mounted on said shaft, said carriage being rockable in unison with said shaft and said shaft being turnable relative to said carriage, said carriage being 60 longitudinally slidale relative to said shaft, a movable printing member located on said carriage and having a plurality of characters thereon, and connecting mechanism intermediate said shaft and said printing member, said connecting 65 mechanism being adapted to actuate said printing member when the shaft is turned, so as to bring a selected character of said printing member into printing position relative to said platen.

2. In a typewriter having a frame and a platen, 70 a shaft mounted in said frame, a carriage mounted on said shaft, said carriage being rockable in unison with said shaft and said shaft being turnable relative to said carriage, said carriage being longitudinally slidale relative to said shaft, a 75

movable printing member located on said carriage and having a plurality of characters thereon, and connecting mechanism intermediate said shaft and said printing member, said connecting mechanism being adapted to actuate said printing member when the shaft is turned, so as to bring a selected character of said printing member into printing position relative to said platen, and a rock member connected to said frame, said 10 rock member being adapted to rock said carriage when said rock member is actuated.

3. In a typewriter having a frame and a platen, a shaft mounted in said frame, a carriage mounted on said shaft, said carriage being rockable in unison with said shaft and said shaft being turnable relative to said carriage, said carriage being longitudinally slideable relative to said shaft, a movable printing member located on said carriage and having a plurality of characters thereon, and connecting mechanism intermediate said shaft and said printing member, said connecting mechanism being adapted to actuate said printing member when the shaft is turned, so as to bring a selected character of said printing member into printing position relative to said platen, said carriage having spaced lips, and a rock member connected to said frame and having a portion thereof located between said lips.

4. In a typewriter having a frame and a platen, a first shaft mounted in said frame, a sleeve mounted on said first shaft, said sleeve being rockable in unison with said first shaft and being longitudinally slideable relative to said first shaft, a gear connected to said sleeve and movable in unison therewith, a carriage, means connecting said carriage to said sleeve so that the carriage can move in unison with said sleeve, said first shaft and said sleeve being turnable relative to said carriage, an upstanding shaft mounted in 40 said carriage and having a second gear which meshes with the first-mentioned gear, a printing member connected to said shaft and turnable therewith, and mechanism for rocking said carriage and first shaft in unison so that the printing member moves towards and away from the platen.

5. In a typewriter having a frame and a platen, a printing member, a carriage adapted to support said printing member for longitudinal movement and also for movement towards and away from said platen, a pivoted arm connected to said carriage, said arm being of sufficient length so that an end of said arm contacts with a fixed portion of the frame during the movement of the printing member towards said platen and before said printing member arrives at the printing position, the pivotal connection of said arm to said carriage being longitudinally offset relative to said end of said arm, so that the movement of the carriage towards the platen causes said arm to shift said carriage longitudinally before said printing member arrives at the printing position, the fixed part of the frame having rack teeth which are shaped to cooperate with the end of said arm, said carriage also having a rack member movably connected thereto and adapted to contact with said rack teeth of the frame, spring means mounted on said carriage and adapted to urge said rack member towards the rack teeth of the frame, the teeth of the rack member meshing only partially with the rack teeth of the frame when the printing member is in its normal position, said carriage also having manually operable means for moving said rack member away from the rack teeth of the frame.

6. A typewriter having a frame and a platen, a rock shaft 38 mounted in said frame, a sleeve 37 mounted on said rock shaft, said sleeve 37 being rockable in unison with said rock shaft 38, said sleeve 37 being longitudinally slideable on the rock shaft 38, a carriage mounted on said sleeve 37, said carriage having an upstanding shaft 34, a first gear 35 connected to said upstanding shaft 34, said sleeve 37 having a second gear 36 being in mesh with the first gear 35, a printing member mounted on the upstanding shaft 34, said frame having a longitudinal row of rack teeth 29, a rack member 67 slidably connected to said carriage, said rack member 67 being movable towards and away from the rack teeth 29, a spring 69 connected to said carriage and connected to said rack member 67 and operative to urge said rack member 67 towards the rack teeth 29, stop means adapted to limit the sliding movement of the rack member 67 relative to said carriage and in a direction towards said rack teeth 29, an arm 70 pivoted to said carriage, a spring 73 connected to said carriage and connected to said arm 70, and adapted to turn said arm 70 so that an end thereof is moved towards said rack teeth 29, a manually operable member 65 pivotally connected to said carriage and adapted to move the rack member 67 away from the rack teeth 29 and to turn the arm 70 so that said end of the arm 70 is moved away from the rack teeth 29, the arm 70 being connected to said carriage by a pivot 71 which is longitudinally offset relative to said end of the arm 70, means connected to the frame and adapted to rock the sleeve 37 and the rock shaft 38 in unison so that the printing member is moved towards the platen, said sleeve 37 and said shaft 38 being turnable relative to said carriage, spring means adapted to hold the carriage in predetermined normal position relative to the platen, the teeth 40 of the rack member 67 and said end of the arm 70 meshing only partially with the rack teeth 29 in said normal position of the carriage.

7. In a typewriter having a frame and a platen, a rock shaft 38 mounted in said frame, a sleeve 37 mounted on said rock shaft 38 and rockable in unison with said rock shaft 38, said sleeve 37 being slideable on the rock shaft 38, upstanding arms 52 connected to said sleeve 37, a carriage member located between and connected to said upstanding arms 52, said carriage member having first and second spaced webs 42 and 44 which have an intermediate web 43, said second web 44 having an extension web 45, said extension web 45 having a first lip 46, a supplemental member 49 which is connected to the extension web 45, said supplemental member 49 having a second lip 50, a rock member connected to the frame and having an extension 79 which is located between the first and second lips 46 and 50, said rock member being manually operable and having a spring 80 which holds said rock member yieldingly in a predetermined position, a second shaft 34 mounted in said first and second webs 42 and 44, a printing member connected to said second shaft 34, a first gear 35 connected to the second shaft 34, a second gear 36 connected to the sleeve 37 and meshing with the first gear 35, the frame having a longitudinal row of rack teeth 29, the first web 42 having a rack member 67 slidably connected thereto, a spring 69 connected to the rack member 67 and to the first web 42 and adapted to move the rack member 67 towards the rack teeth 29, an arm 70 pivotally connected to the first web 42 at 71, said arm 70 having an end which meshes only 75

partially with the rack teeth 29 when said rock member is in its normal position, the teeth of the rack member 67 also meshing only partially with the rack teeth 29 in said normal position of the 5 rock member, the first web 42 and the rack member 67 having cooperating stop means for limiting the movement of the rack member 67 relative to the first web 42 and towards the rack teeth 29, the first web 42 and the arm 70 having cooperating 10 stop means adapted to limit the movement of said end of the arm 70 towards said rack teeth, a member 65 pivotally connected to the first web 42, said member 65 having separated portions adapted to move the rack member 67 away from the 15 rack teeth 29 and to turn the arm 70 so that said end thereof is moved away from said rack teeth 29 when the member 65 is turned, the pivot 71 of

the arm 70 being longitudinally offset relative to said end thereof, said end of the arm 70 and the teeth of the rack member 67 being only partially in mesh with the rack teeth 69 when said rock member is in its normal position.

8. A typewriter having a frame and a platen, a carriage slidably mounted on a member which is connected to said frame, said carriage being also movable towards and away from the platen, an annular and turnable printing member mounted 10 on said carriage, a ribbon, said carriage having guide means through which the ribbon passes, said carriage being slidable relative to said ribbon, said guide means being adapted to hold the corresponding portion of said ribbon in curved form. 15
